F. D. HOLDSWORTH

CONTROLLING MECHANISM

Filed July 6, 1920

Fig. 1.

UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Application filed July 8, 1920. Serial No. 394,297.

To all whom it may concern:

Be it known that I, FRED D. HOLDSWORTH, a citizen of the United States, residing at Claremont, in the county of Sullivan and State of New Hampshire, have invented certain new and useful Improvements in Controlling Mechanisms, of which the following is a full, clear, and exact specification.

My invention relates to controlling mechanisms and more particularly to compressor controlling mechanisms.

An object of my invention is to provide an improved compressor controlling means. Another object of my invention is to provide an improved controlling mechanism for motor driven compressors of the type wherein the motor is stopped and started and the compressor loaded and unloaded in accordance with variations in compressor discharge or receiver pressure. Further objects of my invention will appear in the course of the following specification and claims.

In the accompanying drawings I have shown for purposes of illustration, one form which my invention may assume in practice.

In these drawings,—

Fig. 1 is a side elevation of a compressor system provided with my improved controlling mechanism, a portion of the compressor cylinder being broken away to show the inlet valve mechanisms.

Fig. 2 is a central vertical section through the control mechanism which I have used as an illustrative embodiment of my invention.

Fig. 3 is a detail on an enlarged scale on the same line as Fig. 2.

Fig. 4 is an enlarged sectional view of the switch mechanism.

I have shown my improved compressor controlling mechanism in combination with a compressor system comprising a compressor 1 having a cylinder 2, discharge mechanism generally indicated by 3, and inlet mechanism generally indicated by 4 and which will be more fully described later. The compressor 1 is driven by a motor 5 which is supplied with current through mains 6 and 7 under control of a switch 8 which is of the magnetic control type, being controlled by the magnet 9 and the latter is controlled by mechanism which will be described hereafter. The compressor inlet mechanism consists of a plurality of inlet valves 10 of which but one is shown, these valves being provided with stems 11 and

being normally held closed by a spring 12 which is of such strength as to be overcome by the suction produced by the movement of the piston on the suction stroke. For the purpose of unloading the compressor, plungers 13 are provided in cylinders 14. These plungers, when subjected to fluid pressure on their lower sides, tend to raise the stems 11 and accordingly maintain them open whereby the air is permitted to pump into and out of the cylinder as the piston reciprocates. Fluid pressure is supplied to and conducted away from the cylinders 14 by piping 15 which is under the control of my improved mechanism, the details of which will now be described.

For the purpose of controlling both the operation of the motor 5 and the position of the inlet valves, I have provided controlling mechanism whose illustrative embodiment is most clearly illustrated in Fig. 2. This mechanism comprises a cylinder 16 in which a piston 17 is reciprocable, the piston being subjected to the action of a spring 18 which normally holds it at the top of its cylinder 16 and being adapted to be moved downward by fluid pressure transmitted to the top of the chamber 16 by way of a port 19. At this point attention is directed to the fact that a large clearance volume is provided as indicated at 20 at the top of the chamber 16, the purpose of this clearance volume being to provide a considerable quantity of air in the cylinder, which air will take a considerable time to exhaust, as later described. The port 19 is controlled by a check valve 21 and the check valve 21 is provided with a central vent of small size as indicated at 21'. Fluid pressure is supplied to the check valve which opens toward the cylinder 16 by way of the connection 22 and the latter is controlled by means of a well known type of pilot valve, here shown as the Judson type. This pilot valve, which is designated 23, has a connection 24 with the receiver 25 which receives the discharge from the compressor cylinder 2 and is also provided with a small exhaust port 26. The operation of the pilot valve, as is well known, is such that upon rise of receiver pressure above a desired limit, the pilot valve will open and transmit the pressure through the connection 22 while closing the exhaust 26. When, however, the pressure falls below a certain slightly lower desired limit, the pilot

valve will close the communication between the connections 24 and 22 and will place the connection 22 in communication with the exhaust 26, thereby placing the cylinder 16 in communication with the atmosphere. It will thus be seen that the piston 17 will be caused to move downwardly at such time as fluid pressure in the receiver exceeds a predetermined desired amount, and will move 10 backward at a retarded rate due to the necessity of fluid pressure escaping from above it by way of the vent 21' in the check valve 21 upon the falling of the pressure within the receiver below a predetermined desired 15 limit. The piston 17 is provided with a projecting rod 27 which carries at its lower end a cross head 28 and the latter moves in a cylindrical guide chamber 29 secured to the lower end of the cylinder member 16. At 20 the bottom end of the cross head member is an adjustable contact element 30 which is in turn adapted to impinge upon a pin 31 which controls a switch 32 of a well known type, the switch 32 being so arranged at the 25 lower end of the guide member 29 as to have its control pin 31 impinged by the contact member 30 when the piston 17 reaches the bottom end of its stroke. The switch 32 is so constructed that when the member 31 is forced downwardly the circuit 33, which 30 controls the magnet 9, is opened, thereby causing the opening of the main circuit through the motor 5 and upon release of the plunger 31 by upward movement of the piston, the circuit 33 through the magnet 9 is 35 at once closed in such a manner that the motor resumes operations.

From the foregoing description of the operation of the piston 17, it will be obvious that the motor will be promptly stopped and promptly started in accordance with variations in pressure in the receiver.

For the purpose of controlling the inlet valves I have arranged a valve 34 controlling the communication of a connection 24' with the piping 15. The valve 34 is provided with a surface 35 adapted to cooperate with a stationary seating surface 36 and is provided with radially extending holes 37 opening into the interior of the valve. The valve is also provided with a surface 38 opposite the surface 35 which is adapted, when the valve is in its opposite position, to seat upon a stationary annular seating surface 39 and the valve is adapted to be moved in opposite directions by fluid pressure and by a plunger 40 which is slidably mounted in an opening in the valve casing 41. The plunger 40 is surrounded by an annular exhaust port, extending up to the seating surface 39, and this exhaust port, indicated here as 42, communicates with the atmosphere as indicated at 43. It will be obvious that as the plunger 40 is pressed to the right the surface 35 will seat upon the seat 36 and close communica-

tion between connections 24' and 15, while opening a communication between connection 15 and the atmosphere by way of openings 37, 42, and 43, and that in the reverse position of the valve, a communication between pipes 35 and 15 will be opened, while the seating of the surface 38 on the surface 39 will prevent communication of the pipe 15 with the exhaust. For the purpose of controlling the operation of the plunger 40 I have arranged a cylindrical transverse opening 44 through the cross head member 28 and mounted herein two balls 45 which are of a greater combined diameter than the diameter of the cross head member 28. For 70 the purpose of actuating the plunger 40 I have arranged a spring 46 which is mounted in a shallow notch 47 extending longitudinally of the member 29. This spring 46 constitutes in effect a lever, being fixed at its 75 lower end and having its upper end engaging the plunger 40 so that when pressure is applied adjacent the upper end of the member 46, the plunger 40 is moved bodily. As will be noted, when the cross head 28 is at 80 the bottom of its travel, the spring or lever is relieved of the pressure exerted upon it by the balls 45 and pressure through the connection 24' will open the valve 34 and supply fluid to the plungers 14, the connection 85 to the exhaust being closed at this time. When the cross head 28, however, reaches the position shown in Fig. 2, i. e., the opposite end of its stroke, the balls 45 force the spring 46 against the plunger and close the 90 connection between pipes 24' and 15 and place pipe 15 in communication with the exhaust. As will be observed that owing to the 95 resilience of the lever or spring 46, the movement of the valve will be very sharp and it will snap from its left hand position to its right hand position as soon as a sufficient pressure is exerted upon the member 46 by the balls to cause the pressure to move the valve off of its seat upon the surface 39. 100

The operation of the device is as follows:

When the pressure in the receiver 25 exceeds a predetermined amount, the pilot valve 23 will operate to supply pressure through connection 22 and check valve 21 to the cylinder 16 and force downward the piston 17 therein. The piston 17 in its downward movement causes the cross head 28 to move downwardly and progressively frees the spring 46 due to the releasing 115 thereof by the movement away from its free end of the balls 45. The valve 34 will accordingly open and fluid pressure from the receiver will be transmitted by way of passage 24' and passage 15 to the plungers 14 and cause the opening of the inlet valves 10 and maintain them in an open position. The contact member 30 will also impinge upon the plunger 31 and so open the circuit controlling the magnet 9, and so the main 120 125 130

switch 8 will be opened and the compressor motor stopped. As a result, the compressor plant will be completely shut down. When the pressure in the receiver falls to a desired degree, the pilot valve 23 will be operated to close communication between the line 24 and the connection 22 and will open the exhaust port 26. The piston 17 will accordingly be moved upward by the spring 18 as rapidly as the air within the upper end of the cylinder and the chamber 20 can be expelled through the vent 21 in the check valve 21. The upward movement of the piston will first free the switch controlling pin 31 and thereby cause the starting of the compressor motor due to the fact that the magnet circuit having been closed, the main circuit will likewise be closed. When, after the interval occasioned by the delay in the upward movement of the piston 17, the cross head 28 moves up sufficiently far to place the spring 46 under such pressure as to overcome the air pressure acting upon the surface 35, the valve 34 will interrupt communication between connections 24' and 15 and will simultaneously open communication by way of ports 37, 42 and 43 between the pipe 15 and the atmosphere, thereby permitting the plungers 13 to fall and the inlet valves to close. As a result, the compressor will be loaded, but, due to the delay during the escape of the fluid from the top of the cylinder 16 and from the chamber 20 through the restricted vent 21' in the check valve 21, the motor will have brought the compressor to full speed prior to the time when a load is thrown upon it. It will be noted that when the valve 34 is first moved by the plunger 40 from its left hand seated position, additional area will become exposed to pressure and so the spring 46 will effect a sharp throw of the valve.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a compressor controlling mechanism, in combination, compressor unloading means and a controlling valve therefor, a lever contacting therewith adjacent one end thereof and having a fixed fulcrum, and force applying means moving relatively longitudinally of said lever in consequence of compressor discharge pressure variations.

2. In a compressor controlling mechanism, in combination, compressor unloading means and a controlling valve therefor, a lever contacting therewith adjacent one end

thereof and having a fixed fulcrum, and force applying means moving relatively longitudinally of said lever to decrease the distance between the point of application of the force and the point of contact with the control valve in consequence of compressor discharge pressure variations. 70

3. In a compressor controlling mechanism, in combination, compressor unloading means including a control valve and a flexible lever for actuating the same, and means movable in response to compressor discharge pressure variations in a direction generally longitudinally of said lever, to vary the flexure of said lever adjacent its point of contact with the control valve. 75

4. In a compressor controlling mechanism, in combination, a compressor unloading mechanism, a control valve therefor, and means for moving said valve sharply including a flexible lever for actuating said valve and means movable in consequence of compressor discharge pressure variations operative to flex said lever to cause the latter to impose upon said valve an increasing pressure. 80

5. In a compressor controlling mechanism, in combination, a fluid pressure operated unloading mechanism, a control valve therefor operative in opposite positions to cause supply of fluid to said mechanism to unload the compressor and to connect said mechanism with exhaust to cause loading of the compressor, said valve being biased to the first named position by fluid pressure, and means including a flexible lever and means for flexing the same to cause said valve to move sharply from first to second position. 95

6. In a compressor controlling mechanism, in combination, a fluid pressure operated compressor unloading mechanism, a control valve therefor, and means for moving said valve sharply including a flexible lever for actuating the valve, said lever being movable in consequence of compressor discharge pressure variations and operative when positively moved to shift said valve to interrupt supply of fluid to said pressure unloading mechanism and open a vent therefrom. 100

7. In a compressor controlling mechanism, in combination, a compressor unloading means, a controlling valve therefor, a resilient lever for actuating the latter, and means movable in consequence of compressor discharge pressure variations to cause said lever to release said valve to permit the movement thereof in one direction and to move said valve sharply in the opposite direction and elastically retain it in its opposite position. 115

8. In a compressor controlling mechanism, in combination, a compressor unloading means, a controlling valve therefor cooperating with opposed seats, a flexible lever for actuating the valve to move the same 120

sharply from one seat to another, and means movable in consequence of compressor discharge pressure variations to move said lever and having a greater range of movement than the portion of said lever with which it cooperates.

9. In a compressor controlling system, in combination, a compressor, a driving motor therefor and a receiver, driving motor starting and stopping means, control means therefor, compressor unloading means, controlling means therefor, a member reciprocable in consequence of receiver pressure variations, a member movable therewith, a contact device on said second mentioned member adapted to actuate said first mentioned controlling means, a flexible member engageable with said second mentioned controlling means, and means carried by said second mentioned member having rolling contact with said last mentioned member, and operative to force the same into yielding contact with said second mentioned controlling means.
10. In a compressor controlling system, in combination, a compressor, a driving motor therefor and a receiver, driving motor starting and stopping means, control means therefor, compressor unloading means, controlling means therefor, a member reciprocable in consequence of receiver pressure variations, a member movable therewith, a contact device on said second mentioned member adapted to actuate said first mentioned controlling means.
11. In a compressor controlling system, in combination, a compressor, a driving motor therefor and a receiver, driving motor starting and stopping means, control means therefor, compressor unloading means, controlling means therefor, a member reciprocable in consequence of receiver pressure variations, a member movable therewith, a contact device on said second mentioned member adapted to actuate said first mentioned controlling means.

trolling means, a flexible member engageable 35 with said second mentioned controlling means, and a ball rotatably mounted in said second mentioned member having rolling contact with said last mentioned member and operative to force the same into yielding contact with said second mentioned controlling means.

12. In a compressor controlling mechanism, in combination, compressor unloading means 45 and a controlling valve therefor, a lever contacting therewith adjacent one end thereof and having a fixed fulcrum, a guide making a small angle with said lever, and force applying means moving relatively longitudinally of and between said lever and guide 50 in a direction toward the vertex of said angle in consequence of compressor discharge pressure variations.

13. In a compressor controlling mechanism, in combination, compressor unloading means 55 and a controlling valve therefor, a lever contacting therewith adjacent one end thereof and having a fixed fulcrum, and force applying means having a rotatable member 60 which engages said lever and is adapted to roll therealong, and moving relatively longitudinally thereof to decrease the distance between the point of application of the force and the point of contact with the control valve in consequence of compressor discharge 65 pressure variations.

In testimony whereof I affix my signature.
FRED D. HOLDSWORTH.
